US00D748681S

(12) **United States Design Patent**
Renski et al.

(10) **Patent No.:** US D748,681 S
(45) **Date of Patent:** ** Feb. 2, 2016

(54) **TIP FOR A GROUND ENGAGING MACHINE IMPLEMENT**

(71) Applicant: **CATERPILLAR, INC.**, Peoria, IL (US)

(72) Inventors: **William J. Renski**, Peoria, IL (US);
Thomas Marshall Congdon, Dunlap, IL (US)

(73) Assignee: **Caterpillar Inc.**, Peoria, IL (US)

(**) Term: **14 Years**

(21) Appl. No.: **29/517,824**

(22) Filed: **Feb. 17, 2015**

Related U.S. Application Data

(62) Division of application No. 29/487,373, filed on Apr. 8, 2014, now Pat. No. Des. 727,980, which is a division of application No. 29/403,592, filed on Oct. 7, 2011, now Pat. No. Des. 706,311.

(57) **CLAIM**

The ornamental design for a tip for a ground engaging machine implement, as shown and described.

DESCRIPTION

FIG. 1 is a perspective view of a first embodiment of a tip for a ground engaging machine implement showing our new design;

FIG. 2 is a front view thereof;

FIG. 3 is a front view thereof with the front elevated;

FIG. 4 is a left side view thereof;

FIG. 5 is a right side view thereof;

FIG. 6 is a rear view thereof;

FIG. 7 is a top view thereof;

FIG. 8 is a bottom view thereof;

FIG. 9 is a rear perspective view thereof;

FIG. 10 is a perspective view of a second embodiment of a tip for a ground engaging machine implement showing our new design;

FIG. 11 is a front view thereof;

FIG. 12 is a front view thereof with the front elevated;

FIG. 13 is a left side view thereof;

FIG. 14 is a right side view thereof;

FIG. 15 is a rear view thereof;

FIG. 16 is a top view thereof;

FIG. 17 is a bottom view thereof; and,

FIG. 18 is a rear perspective view thereof.

The broken lines illustrate structure or features that form no part of the claimed design.
